UNITED STATES PATENT OFFICE.

GEORGE A. MACBETH, OF PITTSBURG, PENNSYLVANIA.

COMPOSITE LENS.

No. 832,916.

Specification of Letters Patent

Patented Oct. 9, 1906.

Application filed February 26, 1906. Serial No. 302,929.

To all whom it may concern:

Be it known that I, GEORGE A. MACBETH, a citizen of the United States, residing at Pittsburg, in the county of Allegheny and State of Pennsylvania, have invented certain new and useful Improvements in Composite Lenses, of which the following is a specification.

The invention relates to lamp lenses, and has for its objects to provide a powerful lens adapted to transmit light freely through all portions thereof of such construction that the interior of the lamp may be observed through the lens without distortion and by which means the condition of the flame may be conveniently noted from the front without the necessity of opening the lamp; and to provide a lens of simple and inexpensive construction which when transmitting light will present a new and attractive appearance and one in which the full efficiency of the light may be utilized. One form of the invention is shown in the accompanying drawing, in which—

Figure 1 is a side elevation of the lamp to which the lens is applied with the center thereof broken away to show a section of the lens and the interior of the lamp, and

Figure 2 is a front view of the lamp.

In lenses of this general type it is of course desirable that the light from the lamp be brought into parallelism by means of a refracting lens of some sort or other, and it has been customary to make them in a variety of shapes, as plano-convex, convex or concave-convex with corrugations, whereby the light may be refracted in the desired direction, but all of these lamps are open to the objection that after the lamp has been lighted and closed it is impossible to judge accurately the condition of the flame by looking into the lamp from the front, because of the distortion caused by the curvature and thickness of the glass. My lens has been designed to overcome this difficulty by providing a lens in which a portion thereof is of such construction that it will not distort the light, and therefore by means of which the light may be accurately adjusted after the lamp is closed. It has been the design to secure this result without in any way diminishing the efficiency of the lens.

As shown in the drawings, the lens is applied to a vehicle lamp 3 of ordinary construction provided with the illuminating means 4 of any preferred construction, and

the reflector 5 which may also be of any desired type. The lens 6 itself is of the concave-convex type, and is provided with the refracting corrugations 7 of the usual construction, whereby the rays from the light may be brought into substantial parallelism. These annular corrugations are, however, not extended to the extreme circumference of the lens, but are stopped a short distance therefrom, and the remainder of the lens consists of a plain annular band on both front and back faces of the lens, which front and back faces 8 and 9 are parallel and constitute the band 10 as shown in Figure 2. This band constitutes a means whereby the flame may be observed from the front of the lamp without opening it. It will be apparent because of the opposite parallel sides 8 and 9 of the band that no distortion due to refraction will occur when looking through such band, and that the flame may therefore be accurately adjusted. The annular band 10 will not of course bring into parallelism the direct rays from the light as does the corrugated center of the lamp, but such divergent rays are useful in broadening the field of the lamp, and the reflected rays from the concave reflector may be made to pass through such annulus in approximate parallelism with rays through the corrugated center. When lighted the face of the lamp presents an attractive appearance, and it will be further observed that the full efficiency of the lamp is preserved, although the field is somewhat broadened by the divergence of the direct rays through the band 10.

It will also be noted that from a manufacturing standpoint the construction is advantageous in that the thickness of the glass from the edges to the center varies slightly, obviating any strains in cooling which are induced in a glass of widely varying thickness, such as a lens with a band similar to 10, and a convex bull's-eye. The construction also results in saving of weight over the convex bull's-eye, and a better and more uniform transmission of light.

Other advantages will be apparent to those familiar with the art.

Having thus described my invention and illustrated its use, what I claim as new, and desire to secure by Letters Patent, is the following:

1. A convex concave lens of substantially uniform thickness throughout and having a uniformly curved front face and a rear face

having the same general curvature as the front face but provided with a smooth annulus and a plurality of raised refracting rings.

- 5 2. In combination, a lens comprising a central refracting portion adapted to parallelize the rays of light, and an annulus, the faces of which are substantially parallel, a concave reflector, and a lamp interposed between the lens and the reflector, all so arranged that a part of the reflected rays pass

through the annulus in parallelism while the direct rays from the lamp pass therethrough in a diverging direction.

In testimony whereof I have hereunto signed my name in the presence of the two subscribed witnesses.

GEO. A. MACBETH.
